UNITED STATES PATENT OFFICE.

VALENT HOVANEC, OF AMBRIDGE, PENNSYLVANIA.

TOOL HOLDER.

1,422,058.

Specification of Letters Patent.

Patented July 4, 1922.

Application filed November 5, 1921. Serial No. 513,155.

To all whom it may concern:

Be it known that I, VALENT HOVANEC, a citizen of the United States of America, residing at Ambridge, in the county of Beaver and State of Pennsylvania, have invented certain new and useful Improvements in Tool Holders, of which the following is a specification.

This invention relates to certain new and useful improvements in tool holders and more especially to those of that character or type which are socketed to receive the shank of a tool and adapted to be nested together in order that tools of different sizes may be used with the same machine press or spindle.

The primary object of this invention is to provide a plurality of socketed tool holders of different sizes nested together in an improved manner whereby change from one sized holder to another may be readily accomplished in a desirable manner.

Another object is to provide the inner tool holder with means for locking a tool in the socket thereof and engageable by the outer holder for preventing release of the tool until said outer holder is removed.

With the above general objects in view and others that will appear as the nature of the invention is better understood, the invention consists in the novel form, combination and arrangement of parts herein-after more fully described in connection with the accompanying drawing, in which like characters designate corresponding parts throughout the several views.

In the drawings,

Figure 1 is a view in side elevation of tool holders of different sizes nested together in operative relation and carrying a drill, part of which is broken away,

Figure 2 is a view similar to Figure 1 looking toward the right.

Figure 3 is a substantially central vertical sectional view of the device shown in Figures 1 and 2,

Figure 4 is a vertical sectional view of the lower portion of the device shown in Figure 3 with the plane of section at right angles to the plane of section in Figure 3,

Figure 5 is a horizontal sectional view taken upon line V—V of Figure 3,

Figure 6 is a side elevational view, partly broken away, of the form of tool adapted to be employed with the present tool holders, and

Figure 7 is a side elevational view of a form of lock releasing tool which may be employed for releasing the lock of the intermediate sized tool holder.

Referring to the drawing, wherein a plurality of drill sleeves are shown as being constructed to embody the present invention, 5 designates the smallest drill sleeve or holder having a tang 6 at its upper end and provided with a short longitudinally extending slot 7, adjacent said tang, said sleeve or holder being also provided with a longitudinally extending socket adapted to receive the shank end of a drill 8 or other tool.

A second and largest tool holder 9 has a longitudinally extending socket adapted to receive the shank end of a larger drill or tool corresponding in size to the smallest tool holder 5 so that the latter may be received in the socket of the holder 9 as clearly illustrated in Figures 3 and 4, the holder 9 being provided with a slot 10 at the inner end of its socket for reception of the tang 6 whereby relative rotation of the holders 5 and 9 is prevented, and the holder 9 being provided with a short longitudinally extending slot 11 communicating with the slot 10 to give access to a drift pin for the usual well known purpose, this being also the purpose of providing the slots 7.

In accordance with the present invention, the tool employed will involve a tang 12 to be received in the inner end of the socket of each holder whereby relative rotation of the holder and tool is prevented and the shank of the tool will also be reduced adjacent the tang 12 as at 13 to provide and annular bottom shoulder 14. When the tool is of such size as to be employed in the holder 5, the shoulder 14 will be in position to be engaged by the lower hooked end of a catch 15 which is pivoted upon a horizontal axis as at 16 to the holder 5 within a side slot 17 provided in said holder 5, and the construction will be such as to have the outer edge of the catch 15 lie substantially flush with the outer surface of the holder 5 when said catch is in locking position so that when the largest holder 9 is disposed on the holder 5, the first named holder will prevent removal of the tool 8 and prevent access to the catch 15 for this purpose.

The largest holder 9 is also provided with a side slot beside the slots 10 and 11 as at 18 in which a further catch 19 is pivoted upon a horizontal axis as at 20, said catch

19 being provided with a hooked end adapted to engage the shoulder 14 of a tool when within the socket thereof and being normally swung to locking position by means 5 of a spring 21 placed between the holder 9 and the upper end of the catch 19 within a socket provided in said holder 9 at the upper end of the slot 18. When the holder 9 has the holder 5 therein and is accordingly 10 not serving to hold a tool, the angular lower end of the catch 19 will be in position to engage a corresponding shoulder 14' provided on the holder 5 near the tang 6 thereof by reducing the upper end of said 15 holder 5.

The largest holder 9 is provided with a reduced upper end providing an extension or shank 22 adapted to be snugly received within the socket of an intermediate sized 20 holder 23 whose socket is also adapted for snug reception of the shank end of an intermediate sized tool, and the shank 22 is reduced or cut away near its upper end to provide a shoulder or shoulders 24 slightly 25 below a tang 25 provided upon the upper end of said shank 22. The socket of the holder 23 may be provided to snugly receive the tang 25 and particularly to engage opposite sides of said tang as indicated in cross 30 section by Figure 5 whereby relative rotation of the holders 9 and 23 is prevented.

The holder 23 is provided with a socket or chamber 26 above the tang 25 communicating at one side with a side slot 27 provided 35 in the holder 23, in which slot 27 a catch 28 is pivoted upon a horizontal axis as at 29. The catch 28 is provided with a hooked lower end adapted to engage the shoulder 24 for securely retaining the shank 22 within 40 the socket of the holder 23 or to engage the shoulder 14 of the proper tool for retaining the latter in place. The catch 28 is provided with a lateral extension upon its upper end directed inwardly so as to lie in line 45 with an axial opening 30 provided in the upper end of the holder 23 and to overlie the tang 25 of the shank 22 or the tang 12 of the tool. A spring 31 may be interposed between the lateral extension of the catch 28 50 and the tang 25 or 12 for urging the catch 28 to locking position and said catch may be forcibly released against the action of the spring 31 by forcing downwardly upon the lateral extension of said catch. This may 55 be accomplished by means of a tool such as shown in Figure 7 involving a stem 32 adapted to extend through the opening 30 and engage the upper surface of the lateral extension provided on the upper end of the 60 catch 28, said stem 32 being preferably provided with a handle 33 for its convenient manipulation. In the preferred construction of the holder 23, the slot 27 is made comparatively large at its upper end for the 65 insertion of the catch 28 and the spring 31

and this enlarged upper portion of the slot 27 may be subsequently covered by means of a plate 34 screwed or otherwise held to the holder 23.

If the size of drill which is desired to be 70 employed is the smallest one or that adapted to be received by the holder 5, said tool is placed within the socket of the holder 5 and the latter is then positioned in the holder 9 as shown so that the catch 15 is effectively 75 held in engagement with the shoulder 14 while the shank 22 is held within the socket of the holder 23 by means of the catch 28, and it is noted that the upper end of the holder 23 is so formed as to be held in the 80 chuck provided on the usual machine spindle.

Should an intermediate sized drill be desired, the pin 32 may be inserted in the opening 30 so as to release the catch 28 whereupon the holders 5 and 9 may be separated from the holder 23 without disturbing the relation of the holders 5 and 9 and the tool carried by said holder 5. On the other hand, should the larger socket 9 be desired, the 90 catch 28 is not disturbed but the catch 19 is manually released so as to allow withdrawal of the holder 5 without disturbing the relation of the latter holder and its tool 8.

From the foregoing description, it is believed that the construction and operation as well as the advantages of the present invention will be readily understood and appreciated by those skilled in the art.

Minor changes may be made without departing from the spirit and scope of the invention as claimed.

What is claimed as new is:

1. A plurality of socketed tool holders of different sizes nested together, and means operable to lock a tool within the smaller tool holder and engageable by the next larger tool holder for preventing separation of the tool and the first named holder until said holders are separated, means carried by the larger tool holder to engage the smaller tool holder for retaining said tool holders nested and adapted to engage and retain a larger tool, said larger tool holder having a shank on one end thereof, and a further intermediate sized socketed tool holder adapted for snug reception of said shank, said last named tool holder being provided with means engageable with said shank to retain the latter within the socket thereof and to engage an intermediate sized tool for retaining the latter in said socket thereof.

2. A plurality of socketed tool holders of different sizes nested together, and means operable to lock a tool within the smaller tool holder and engageable by the next larger tool holder for preventing separation of the tool and the first named holder until said holders are separated, means carried by the larger tool holder to engage the

smaller tool holder for retaining said tool
holders nested and adapted to engage and
retain a larger tool, said larger tool holder
having a shank on one end thereof, and a
5 further intermediate sized socketed tool
holder adapted for snug reception of said
shank, said last named tool holder being
provided with means engageable with said
shank to retain the latter within the socket
10 thereof and to engage an intermediate sized

tool for retaining the latter in said socket
thereof, the last named tool holder being
provided with an axial opening in the up-
per end thereof, and said last named means
including a pivoted spring pressed catch 15
having an inward lateral extension releas-
able by an instrument inserted through said
opening.

In testimony whereof I affix my signature.
VALENT HOVANEC.
